UNITED STATES PATENT OFFICE.

WALTER J. HARVEY, OF TORONTO, ONTARIO, CANADA.

LUXOSTAT.

1,200,346.

Specification of Letters Patent.

Patented Oct. 3, 1916.

Application filed November 18, 1915. Serial No. 62,169.

To all whom it may concern:

Be it known that I, WALTER JAMES HARVEY, a subject of the King of Great Britain, and resident of the city of Toronto, county 5 of York, Province of Ontario, in the Dominion of Canada, have invented certain new and useful Improvements in Luxostats, as described in the following specification and illustrated in the accompanying drawings, that form part of the same.

The principal objects of the invention are, to improve the conditions of handling light in ophthalmic and therapeutic work, and to devise an apparatus by which the light is controlled and regulated in quantity, quality 15 and composition to suit the varying requirements.

A further object is to devise an apparatus of this kind which will have considerable 20 latitude of adjustment and which may be handled with ease and accuracy.

A still further object is to provide a reflecting means which may be adjusted to direct the rays of light from a common 25 source in various directions to concentrate the same upon one or more objects or points at the same or various distances from the light source.

The principal feature of the invention 30 consists in the novel construction and arrangement of parts, whereby the rays of light from a suitable generating source are intercepted by a reflector adjustably arranged in relation to the light and diverged 35 or converged thereby and controlled by means adjustably interposed between the reflector and the subject upon which the light is directed.

In the drawings, Figure 1 is a perspective 40 view of a device constructed in accordance with this invention being partly broken away. Fig. 2 is a vertical sectional view of the reflector. Fig. 3 is an enlarged perspective detail of one of the reflecting members 45 showing the adjustable support therefor.

Like numerals of reference indicate corresponding parts in each figure.

Referring to the drawings, 1 is the main 50 supporting bar of the apparatus here shown having the ends 2 upturned and suspended by suitable flexible supports 3 for the purpose of adjustable suspension, the bar may however be rigidly supported if desired.

4 are a plurality of sleeve members in the 55 form of T's slidably and rotatably arranged

upon the bar 1 being locked securely in adjusted positions by the thumb screws 5. Each of the members 4 is provided with an upwardly extending stem portion 6 on the upper end of which are rotatably mounted 60 the T members 7.

8 are tubular arms extending through the head portions of the T's 7 being rotatably arranged therein and adapted to be secured by the thumb screws 9.

10 are T members secured to the outer ends of the arms 8 having the head portions 11 formed with orifices extending perpendicularly therethrough.

12 is a rigid frame here shown of rectangular form having secured to the upper side the threaded rods 13 which extend through the orifices in the head ends 11 of the T's 10.

14 are adjusting nuts threaded upon the upper ends of the rods 13 above the T heads 15 and engaging same and adjustably supporting the frame 12.

15 are sector-shaped plates secured at their outer sides to the side members of the frame 12 by double hinge members 16 and 80 extending inwardly toward the center of the frame.

17 is a small plate centrally arranged between the inner ends of the sector shaped plates 15 and secured to each of said sector 85 plates by the hinges 18.

19 is a threaded spindle pivotally secured to the back of the center plate 17 by the socket plate 20.

21 is a threaded sleeve arranged upon the 90 spindle 19 having a squared central portion 22 arranged between the end flanges 23.

24 is a rigid frame extending across the back of the frame 12 and having a slotted recess 25 adapted to receive the squared 95 portion 22 of the sleeve 21 to hold the same from turning, said recess being open at the top so that the sleeve may be easily entered or removed therefrom.

The spindle 19 is provided with a crank 100 26 on its outer end and is adapted to be rotated to move the center plate 17 toward or from the frame 24 to effect a change in the angular position of the sector plates 15.

27 are a plurality of mirrors here shown 105 in rectangular form each adjustably supported on the sector plates 15 by means of a double swivel connection, which is here shown in the form of a crossed member 28 having the arms 29 thereof pivotally se- 110

cured in the lugs 30 extending outwardly from the back of the mirror frame and the cross arms 31 being pivotally supported in the lug members 32 extending from the back 5 of the plates 15, locking nuts 33 are provided in the outer ends of the arms 29 and 31 in order to secure the reflectors in the desired angular position.

34 is a U-shaped tube having the threaded ends 35 extending upwardly through the T heads 10 supported from one of the members 4 being adjustably supported by the adjusting nuts 14.

36 is a block secured to the lower loop of 15 the member 34.

37 is a rod adjustably arranged in the block 36 supporting at its lower end a suitable lighting medium 38 which is here shown of a simple form of carbon arc.

20 39 is a rectangular frame suspended from the rods 40 which are threaded and adjustably supported in the T heads 10 of another set, said frame being formed to receive suitable screens adapted to intercept 125 the light either from the lighting medium or the reflector, or both, as may be desired.

It will be understood from this description that the reflector, the lighting medium and the screen may all be adjusted longitudinally upon the bar 1 or they may be 30 swung laterally by rotating the members 4 on said bar or they may be swung upon their own central supports formed by the stems 6 of the members 4 into various positions. A great variety of adjustment can thus be obtained in the matter of directing, controlling or diffusing the light. The screen frame is utilized for holding a reflector or one or more screens for diffusion 35 or breaking up of the light into its chromatic, chemical or thermal or other constituents and for regulating the quantity, quality and composition of the light.

In addition to the movements hereinbefore mentioned the several members may be 45 swung from the perpendicular plane by rotating the arms 8 in their supporting bearings. The peculiar construction of the reflecting member herein described allows of 50 a plurality of individual reflecting surfaces being arranged to direct a certain amount of light in one particular spot. Other groups may be arranged to direct the light to another particular spot or all may be 55 arranged to concentrate all of the rays of light to a common point. The adjustment is extremely flexible by reason of the operation of the individual plates and also of the operation of the hinged sector supporting plates, thus allowing of the complete control of range of reflection as well as concentration or diffusion.

The extreme flexibility of adjustment of 60 the entire apparatus allows of perfect control of the parts on which the light is to

be used and provides an apparatus which may be utilized to very great advantage in many forms in the use of a controlled light in addition to therapeutic and ophthalmic work.

What I claim as my invention is:—

1. A luxostat, comprising, a horizontal supported bar member, a plurality of sleeve members slidably and rotatably supported on said bars, transversely arranged rotatable members carried on said sleeve members, a reflector suspended from one of said rotatable members and vertically adjustable thereon, a light modifying means suspended from another of said rotatable members and vertically adjustable, and a light adjustably supported from another of said rotatable members.

2. A luxostat, comprising, a horizontally suspended bar, sleeve members slidably and 85 rotatably arranged on said bar and having upwardly projecting stems, sleeve members rotatably mounted on said stems, arms rotatably mounted in the latter sleeve members, frames vertically adjustably supported from 90 said arms, a light supported from one of said frames, a reflector supported from another of said frames, and a light modifying means supported from another of said frames.

3. A luxostat, comprising, a horizontally suspended bar member, sleeve members slidably and rotatably arranged on said bar, laterally arranged arms rotatably secured to said sleeve members having transverse 100 orifices at their outer ends, frames having arms adapted to extend through the orifices in the aforesaid arms, adjusting nuts threaded upon the upper ends of the frame arms and supporting said frames from said 105 transversely arranged arms, locking means for securing the adjustable members in position, a reflector supported from one of said frames, a screen supported from another of said frames, and a light supported from 110 another of said frames.

4. A luxostat, comprising, a longitudinal supporting member, a frame adjustably suspended from said supporting member, a plurality of reflecting members arranged 115 within said frame, means for tilting the reflecting members at various angles independently the one of the other, a light, and means for modifying the light adjustably suspended from said support.

5. A luxostat, comprising, a longitudinal supporting member, a frame adjustably suspended from said supporting member, adjustable members supported in said frame and adapted to be set in varying angular 125 positions and a plurality of reflecting members supported on each of said adjustable members and each adapted to be adjusted at any desired angle independently the one of the other, a light, and means for modify-

ing the light adjustably suspended from said support.

6. A luxostat, comprising, a longitudinal supporting member, a frame adjustably suspended from said supporting member, a plurality of plate members hinged to said frame and extending inwardly, a centrally adjustable member connected to the inner ends of said plate members, and means for 10 adjustably supporting said central member and moving same to adjust the angles of said plate members, a light, and means for

modifying the light adjustably suspended from said supporting member.

7. A luxostat, comprising, a longitudinal 15 supporting member, a frame adjustably suspended from said supporting member, adjustable plate members supported in said frame and a plurality of reflecting members supported on universal hinges and arranged on said plate members, a light and means for modifying the light adjustably suspended from said supporting member. 20

WALTER J. HARVEY.
